WALL LAMP

Charles W. Clemens, Nashville, Tenn., assignor to Aladdin Industries, Incorporated, Nashville, Tenn., a corporation of Illinois

Application August 18, 1955, Serial No. 37,546

Term of patent 3½ years

(Cl. D48—4)

FIG. 1.

FIG. 2.

Fig. 1 is a left front perspective view of a wall lamp embodying my new design;

Fig. 2 is a side view thereof taken from the left side of the lamp shown in Fig. 1.

The dominant features of my design are shown in solid lines.

I claim:

The ornamental design for a wall lamp, substantially as shown and described.
